CLAIM

The ornamental design for a foam music greeting card, as shown and described.

DESCRIPTION

FIG. 1 is a perspective view of the foam music greeting card of the present invention, in a closed position.

FIG. 2 is a front view of the foam music greeting card of FIG. 1.

FIG. 3 is a rear view of the foam music greeting card of FIG. 1.

FIG. 4 is a top view of the foam music greeting card of FIG. 1.

FIG. 5 is a bottom view of the foam music greeting card of FIG. 1.

FIG. 6 is a left side view of the foam music greeting card of FIG. 1.

FIG. 7 is a right side view of the foam music greeting card of FIG. 1; and,

FIG. 8 is a perspective view of the foam music greeting card of FIG. 1, in an open position.

The broken line showing of portions of the foam music greeting card is included for the purpose of illustrating environmental structure and forms no part of the claimed design.
